COIL SEPARATOR

Harry F. Radlinski, Toledo, Ohio, assignor to
 Surface Combustion Corporation, Toledo, Ohio,
 a corporation of Ohio

Application February 5, 1951, Serial No. 209,459

1 Claim. (Cl. 263—47)

1

This invention relates to apparatus for annealing a stack of cylindrical coils of steel strip. It has long been recognized that radial heat flow through the laminations of a strip coil is relatively slow as compared to the heat flow parallel to the laminations heated from the strip edges, and it has been proposed to provide channelled separators between the coils to permit heat to be applied to the edges of the laminations by hot gases flowing through the channels of said separators. Such channels have been generally radial so that a fan at one end of a central passage through the coils may induce draft therein to provide substantially radial gas flow through said channels. The channels have been formed by ribs on an annular plate or between annular plates for support by the plate. Such plates are subject to severe distortion in service due to rapid heating of the ribs by the hot gases in the channels while the coils are yet cold. In such a case the ribs, and also the plate, tend to expand due to heat while severely restrained by the cold heavy coils, and severe twisting and wrinkling of the plate results.

The present invention aims to provide an improved coil separator and to avoid the foregoing difficulties in a relatively simple and practical manner.

For a consideration of what I consider to be novel and my invention, attention is directed to the following specification and the concluding claim thereof.

In the accompanying drawings forming part of this specification:

Fig. 1 is a vertical sectional view of a typical furnace for annealing a stack of coiled strip.

Fig. 2 is a plan view of a coil separator embodying the present invention.

Fig. 3 illustrates a certain combinational relationship between the coil separator and the inner cover of the coil annealing furnace.

Fig. 4 is a fragmentary detail view of the inner edge of the separator.

Fig. 5 further illustrates the combinational relationship shown in Fig. 3.

The annealing furnace shown in Fig. 1 comprises a portable heating hood 10 for heating a bell type muffle or inner annealing cover 11 disposed over a stack of cylindrical coils 12 of thick sheet steel which is to be annealed. The thickness of the laminations of the coils has been greatly exaggerated for illustrative purposes. The source of heat carried by the heating hood will ordinarily comprise internally fired radiant tubes 13 distributed along the sidewalls of the

hood. For simplicity of illustration only the upper and lower tubes are shown, but as indicated by broken lines 14 there will be additional tubes therebetween.

5 The base of the furnace is generally indicated at 15 and comprises an upstanding peripheral wall 16 on which the heating hood 10 is seated, the seat being surrounded by a sand seal 17. The furnace base also comprises a stand 20 for supporting a column of coils 12, the stand being shown in elevation except for the top plate 21 which is shown in section. This top plate has a central aperture coaxial with a circulating fan 22 which is driven by a motor 23 carried by the underside of the coil stand. The top plate 21 is spaced from the lower portion of the coil stand by radial spacers 24 whereby to provide radial gas passages below said plate for the gas circulated by the fan 22. The inner cover 11 is removably supported on a ledge 25 which surrounds the coil stand and the foot 42 of the inner cover is shown as surrounded by a layer of granular sealing material 26 to prevent objectionable leakage of gas from the inner cover. Some seepage of gas from the inner cover is not objectionable, but rather desirable. A non-oxidizing gas is supplied to the inner cover by a supply pipe not shown but which extends through the coil stand 20 from below.

25 It will be understood that unless the coils 12 are spaced apart to provide gas flow passages therebetween all of the gases circulated by the fan 22 which is of the radial discharge type must enter at the top of the coil stack for downward flow therein. The coils are spaced apart by separators 27 and an orifice plate 30 is placed on top of the coil stack. The purpose of the orifice plate 30 is to restrict the entry of circulated gas to the inside of the stack by way of the top thereof whereby to cause part of the circulated gases to flow laterally inward through channels formed by the coil separators 27.

40 Referring now more particularly to Figs. 2, 4 and 5, the improved coil separator 27 comprises a top planar series of ribs 31 curved in a clockwise direction and a bottom planar series of ribs 32 curved in a counterclockwise direction. The ribs 31 are superimposed on ribs 32 and welded thereto by weldments 33 both at the respective inner ends 35 and 36 of the ribs and the outer ends 37 and 38 of the ribs. A bumper 34 in segment form is secured to the outer ends of the ribs 31 and 32 by weldments 44.

45 The ribs 31 and 32 are curved in the form of circular arcs approximating involute curves to

provide passages between adjacent ribs of each planar series which are of substantially uniform size from the inner end to the outer end of the passage. In this way substantially uniform gas velocities through the passages are maintained with resultant uniformity of heat transfer from the gases to the coils 12. The curved bars also serve to provide rigidity due to the curves as well as maintaining uniform conditions from one passage to another. It will be understood that the bumper 34 is sufficiently spaced from the coils 12, or of sufficiently small diameter relative to the width of the bars or ribs 31 and 32, to allow gas to pass over said bumper and into said passages.

Fig. 3 illustrates the functional purpose of the bumper 34. In cases where the inner cover 11 comprises a corrugated vertical wall 41, it is usually provided with a depending skirt 42 which in service is embedded in a sand seal 26, and an annular plate 40 joining the cover wall and the skirt in a gas tight manner. On the inside of the convolutions of the corrugated wall 41 the plate 40 forms a series of shelves wherein the absence of the bumper 34 an exposed and extended rib of a coil separator 27' may catch when the cover is lifted. This causes great difficulty in removing the inner cover from a stack of coils unless a bumper 34 is employed to contact the inner curves of the corrugated cover and thereby prevent the individual ribs from extending beyond the line of the inner curves of the corrugations.

The depending skirt 42 of the inner cover 11 is preferably formed with the plate 40 into an integral straight angle section, then curved as required, welded to the wall 41, then the unnecessary portions of the plate 40 external to the wall 41 are cut out with an oxy-acetylene torch. When bending this angle structure it is far easier to place the skirt 40 on the inside radius of the wall 41, this also giving a smaller diameter sand seal and less contact surface between the sand and the skirt 40 for the overhead crane to overcome when lifting the inner cover out of the hot sand seal 26.

The separator disclosed has the great advantage of no annular plate to buckle and twist, together with the reduced welding as compared to that required in separators of the prior art. Heat transfer from circulating gases is improved due in part to direct contact between gases in the gas passages and the adjacent upper and lower edges of the strip in the coils and in part to the turbu-

lence at the intersection of the gas streams between ribs 31 and the ribs 32 of opposite planar series. The ribs in these separators must present enough bearing surface to the coils to avoid "cutting" them and producing "stickers," which do not properly uncoil after annealing. Higher temperatures may require closer spacing of the ribs than shown in Fig. 2.

The bumper 34 is cut into segments to form a circumferential, discontinuous bumper and allow the coil separator to move freely in thermal expansion and contraction without the restraint of a continuous outer band about the separator.

Every intersection of ribs of opposite series need not be welded where the separators are handled by crane operated magnets rather than hooks or other such fixtures.

The foregoing discloses an improved coil separator which is easily fabricated and which avoids troubles encountered by the prior art.

I claim:

A coil separator for separating coils in a stack of coils to be heated, comprising, in combination, two aligned series of curved ribs, each rib in each series defining a generally radial curve of substantially involute shape and extending from an inner circle to an outer circle and spaced from the next adjacent ribs in the same series to form gas passages therebetween from the inner circle to the outer circle, the ribs of one series extending outwardly from said inner circle and generally clockwise and the ribs of the other series extending outwardly from said inner circle and generally counterclockwise, the ribs of one series being curved in a manner to cross ribs of the other series, each rib of one series being joined to ribs of the other series, and the ribs of each series forming respectively top and bottom sides of the separator for engagement with the coils to be heated.
